SELF-LEVELING HYDRAULIC LIFT SYSTEM

Lee E. Twist, Los Angeles, Calif.

Application December 16, 1946, Serial No. 716,587

5 Claims. (Cl. 60—97)

1

This invention relates to hydraulic leveling equipment, which may be utilized for such purposes as for automatically leveling the bed of harvesting combines and arranged between the bed and the axles thereof; leveling large airplanes prior to rigging, and arranged between the under surface thereof and the ground or floor; or leveling trailers used as living quarters. The invention will be particularly described hereinafter as applied to the last mentioned specific application by way of example only.

Other objects include: the provision of means for automatically leveling the supported structure under the influence of hydraulic pressure; means for automatically locking the apparatus in self-leveled position when such position is attained; a plurality of lifting units disposed at spaced points under and for supporting a structure; means for inter-connecting said supporting units with a source of fluid; and means for controlling the flow of fluid from certain points to others so as to balance the pressure at all supporting points.

Still other objects will appear as the description of my improvements progresses.

A satisfactory system and apparatus is shown in the annexed drawings, subject to modification within the scope of the appended claims.

In the drawings:

Fig. 1 is a perspective view of a vehicular trailer with my lifting apparatus applied thereto and illustrative of one use of the apparatus;

Fig. 2 is a perspective view of one of the lifting units;

Fig. 3 is an enlarged vertical section of the same;

Fig. 4 is a transverse section of a unit on line 4—4 of Fig. 2;

Fig. 5 is an external view of a unit as viewed in the direction of the arrow 5 in Fig. 4;

Fig. 6 is a sectional view on line 6—6 of Fig. 5;

Fig. 7 is a sectional elevation of a fluid storage tank and associated parts;

Fig. 8 is a section of the storage tank on line 8—8 of Fig. 7;

Figs. 9, 10 and 11 are sections of the tank on lines 9—9, 10—10 and 11—11, respectively, of Fig. 8;

Figs. 12 and 13, are, respectively, sectional views on lines 12—12 and 13—13 of Fig. 10;

Fig. 14 is a schematic diagram showing a control unit in section and a fluid tank in phantom, a plurality of lifting units and connections therebetween; and

Fig. 15 is a sectional elevation of a brake unit

2

for holding an associated ram in adjusted position.

My system includes a storage tank T for holding a quantity of fluid and connected on the suction side with a pump P and thence to a plurality of control valves V, V₁, and V₂ and then to a plurality of hydraulic rams R, R₁ and R₂. There are two lines from each valve to each ram, one feeding fluid under pressure to the ram and the other returning fluid from the opposite side of each ram to the tank. As shown in Fig. 1, the ram units are applied to the bed of a trailer A, for instance, with a single unit R at the front and in the center and two units R₁ and R₂ at the rear backwardly of the rear wheels, thus providing three point suspension for the trailer.

Each unit, as at R in Figs. 1 to 4 inclusive, has a vertically disposed movable cylinder 10 arranged with a bottom 11 and a ball 12 adapted to seat in a socket 13 of a foot 14 and to be self-adjusting to the surface of the ground upon which the foot rests, and a fixed piston 21.

The upper ends of the pistons are fixed to brackets 15 which have one or more webs adapted to be attached to the trailer frame 17, as shown in Fig. 2. Each cylinder has a packed head 19 through which a hollow piston stem 20 is extensible from cylinder 10 as said cylinder is relatively moved. As shown in Fig. 3, pistons 21 have upper and lower portions 22 and 23 between which peripheral packing 24 is compressed. Stem 20 fits into a recess in upper part 22 against an inner flange 25 and a member 26 is screwed into the end of said stem for drawing parts 22 and 23 together and thus holding the pistons assembled for use. Piston 21 divides the cylinder into two chambers 28 and 30.

Members 26 are bored to receive inlet tubes 27 through which a fluid is admitted to chamber 28 of a cylinder below piston 21, while stem 20 has ports 29 at points above the piston for directing fluid from upper chamber 30 into the passage 31 of the stem and thence outwardly as hereinafter described.

Each ram unit includes a fixture 32 attached to the upper end of stem 20 and rigidly braced to bracket 15 as by means of bars 33. Fixture 32 has a fluid inlet 34 connected through tube 27 with chamber 28, and an outlet 35 in communication with chamber 30 through passage 31 and ports 29 of stem 20.

Thus, as fluid is pumped into chamber 28, the cylinder will descend relative to piston 21 and through the fixed connection of the piston with frame 17 (bracket 15, bars 33 and fixture 32) the

frame will be elevated, and as fluid is exhausted from chamber 28 but pumped into chamber 29, the cylinder will be raised.

I refer now to Fig. 14, which shows a hydraulic lift system in which the rams R, R₁ and R₂ are connected with other essential elements. First, the storage tank T is arranged for holding a necessary quantity of operating fluid for dispersal to the several rams and for receiving the used fluid at the completion of or during the operation of the system. The pump P is connected by means of a pipe 35 with the outlet from tank T and serves to withdraw the fluid from the tank and deliver it to points throughout the system as and when required, but preferably through a pipe 36 to an inlet 37, leading to a check valve 38 in a chamber 38a which serves to hold pressure in the system under certain operating conditions to be hereinafter explained. Chamber 38a has a bleeding passage 38c open to the tank T.

Each ram R, R₁ and R₂ has a control valve V, V₁ or V₂, respectively, which is carried by a suitable block 39 preferably mounted in tank T above the level of fluid. Said block also supports check valve 38, restrictor valves 40 and 41 and an operating handle 42. Said block is adapted to be fixedly supported in the upper portion of tank T (Fig. 7). A pendulum 43 is pivotally supported by shaft 44 turning in arms 45, 45 of a yoke 47 which straddles block 39 so that the pendulum may freely swing in the fluid of tank T to an extent limited only by a pair of spaced baffles 46, 46 fixed to the bottom of the tank as shown in Fig. 7. Yoke arms 45 are cross connected above block 39 by a rod 48. Pendulum 43 may also swing on shaft 49 (Fig. 8) mounted in shaft 44 perpendicular thereto, forming a gimbal mounting, and is gravity actuated for regulating valves V, V₁ and V₂ in accordance with the inclination of the supported structure A.

As shown in Fig. 14, the control valves V, V₁ and V₂ are slidably mounted in bores 50, 51 and 52, respectively, formed in block 39 and are open at opposite ends to tank T, and have upper enlarged portions 50a, 51a and 52a and similar lower portions 50b, 51b and 52b which fit their respective bores 50, 51 and 52. Inter-communication between valve bores 50, 51 and 52 is effected by passages 53 having suitable branches and connecting with valve chambers 54 and 54a of valves 40 and 41 at times so that fluid from pump P may flow by check valve 38 and its chamber 38a and a passage 38b by valve 40 into passage 53 under pressure from the pump against the tension of a spring 40a which tends to hold valve 40 closed. Likewise, pressure in passage 53 at times will open valve 41 against the tension of its spring 41a so that fluid may flow into a chamber 55 through a port 55a (Fig. 14). Chamber 55 has a bleeding passage 55b to tank T. A piston 56 is slidable in chamber 55 under the control of pressure from pump P and operates member 42 in the form of a yoke 58 with external arms 59, 59 pivoted to opposite sides of block 39 at coaxial points 60, 60 and connected by a rod 61 to which a knob 62 is attached. (See Figs. 7 to 10, inclusive.) Rod 61 engages the surfaces of a V-shaped groove 63 in the outer end of piston 56 so that as the operating member 42 is swung upwardly or downwardly from a normally central position, the piston 56 will be forced inwardly in chamber 54 for purposes hereinafter explained. A spring 63a is arranged between the side of the tank and rod 61. Yoke arms 59 extend across

arms 45 and are connected thereto by a pin and slot connection 59a.

Block 39 carries members 64, 64 which may be notched at spaced points to receive ball detents 65 held at the ends of arms 59 against the tension of springs 66 for holding the member 42 in adjusted position.

Pendulum 43 is provided with three extending arms 43a, 43b and 43c arranged at 120° to one another (Figs. 7 and 8), the ends of which are connected by tension springs 68 with the tips of valves V, V₁ and V₂, the springs acting to hold short lengths of rod 69, having a ball and socket connection with the ends of the valve stems and arms 43a, 43b and 43c, under tension to provide a suitable joint between the parts, so that as the pendulum 43 swings in any direction one or more of the control valves will be moved to a position for leveling the supported structure.

Referring to Fig. 14, it will be observed that the inlets 34 of ram heads 32 are connected by pipes 70, 71 and 72 with ports 70a, 71a and 72a, respectively, opening into valve chambers 50, 51, and 52 which are regulated by portions 50a, 51a and 52a of valves V₁, V, and V₂. Also, outlets 35 of ram heads 32 are likewise connected by pipes 73, 74 and 75, respectively, with ports 76, 77 and 78 leading to valve chambers 50, 51 and 52 at points closeable by portions 50b, 51b and 52b of valves V₁, V and V₂.

In Fig. 14 I have indicated an accumulator B, which has a housing 85 and an internal diaphragm 86 serving to divide housing 85 into two chambers 87 and 88, for, respectively, receiving fluid and air under pressure. Chamber 87 receives surplus fluid and surplus pressure during the raising operation of the rams through a pipe 89 and a passage 89a connected with valve chamber 38a while chamber 88 is charged with air through an inlet valve 90. The accumulator supplies pressure fluid during the leveling operation.

It will be understood that, due to the unevenness of the terrain on which a vehicle may be set, it is necessary to individually hold the several rams in relative positions for maintaining horizontality of the supported vehicle and for such purpose I provide a brake unit on each ram. Such a unit is illustrated in Figs. 5 and 15, and includes a fixture 95 carried by bracket 15 (Fig. 4), cylinder 96 secured to fixture 95, a piston 97 in said cylinder, and a shoe 98 (see Fig. 3), secured at top and bottom by the bracket but having a cut out portion intermediate its ends and adapted to be clamped against the cylinder 10 of an associated ram.

As shown, particularly in Figs. 4, 5 and 15, two pairs of cams 99 are mounted—one pair at the top and one pair at the bottom—of fixture 95, and are inter-connected as by means of one or more rods 100. Said cams are formed by bending up a sheet metal blank to provide a cam flange 99 at each side of a web of metal 99a. The cams are pivoted on shafts 101 and 102, respectively, supported in the walls of the fixture 95 with their heels 103 abutting the outer surface of shoe 98 and their toes 104 connected to rods 100 so that they will operate together. One or more tension springs 105 are connected at 106 to one pair of cams 99 while the opposite ends of said springs are affixed to a stationary part of housing 95, thereby tending to commonly actuate both of the cams for urging shoe 98 into engagement with cylinder 10. Preferably, a friction lining 98a of suitable material is carried in the known manner by the shoe 98.

Cylinder 96 is stationarily held on housing 95 and piston 97 is movable by fluid pressure so as to operate the cams at times. To such end piston 97 has a piston rod 107 which engages at least one cam 99 and, as shown in Fig. 15, urges all of the cams into disengaged positions of non-frictional engagement, and permits movement of the ram relative to its shoe 98, against the tension of springs 105.

A fluid inlet and outlet 108 is provided below piston 97 in cylinder 96 for admitting fluid under pressure into the cylinders to raise the piston and exhausting the same from the cylinder 96 when the piston 97 is returned by the springs 105 as the fluid pressure in the system is lowered. A compression spring 109 is carried to the bottom of cylinder 96 for holding piston rod 107 in contact with the cam and tends to hold the piston in proper position in the cylinder when the pressure below the piston is insufficient to hold cams 99 in inoperative position. Inlets 108 are commonly connected with a pipe leading from units R, R₁ and R₂ to chamber 38b of block 39. Thus, as operating handle 42 is moved downwardly and held in that position pump P is activated by switch S' (Fig. 7) arms 47 will be raised, raising arms 45 and raising pendulum 43 thus causing arms 43a, 43b, 43c to open valves 50a, 51a, 52a to pressure fluid and opening the valves 50b, 51b, 52b to exhaust fluid from above the rams to the tank. Fluid under pressure from the pump will flow past check valve 38 into chambers 38a and 38b charging the accumulator and also will flow through pipe 110 to each brake unit and will raise pistons 97 and retract cams 99 for releasing brake shoes 98 from ram cylinders 10. When sufficient pressure has been built up the pressure fluid will raise valve 40 and flow through passage 53 and its branches into valve bores 50, 51 and 52 supplying pressure through pipes 70, 71 and 72 to chambers 28 of the ram units through their inlet tubes 27. The cylinders 10 are thus forced downwardly into contact with the ground and the supported structure A is raised. Fluid between the top of the cylinders and the pistons will be returned to the tank through pipes 73, 74, 75. If the structure A is on level ground, all of the valves and rams will operate alike, but if the ground is uneven or inclined in any direction, the valves V, V₁ and V₂ and associated units R, R₁ and R₂ will vary as to their relative extent of operation until the structure A assumes horizontality. The leveling operation is always under the control of pendulum 43 which regulates the movement of valves V, V₁ and V₂ by reason of the connections 111 between the tips 69 of said valves and the yokes of the pendulum. Thus, as the pendulum swings in any direction, one or more of the control valves will move upwardly or downwardly according to a given inclination of structure A and thereby open or close, or regulate the effective open area of ports 50a, 51a and 52a for directing hydraulic pressure to the cylinders 10.

When a predetermined pressure on rams R, R₁ and R₂ (Fig. 14) has been attained, which is adjustable by spring 54a on ball 41 for the particular load, fluid will flow through passage 55a into chamber 55 forcing piston 56 against cross arm 61. The V-slot in end of piston 56 will move operating handle to central position, raising saddle 47 (Fig. 7) pendulum 43 and valves V, V₁, V₂ and deactivate the pump by releasing switch S₁. This is the leveling period, at which time the accumulator 38 (Fig. 14) will come into action. All valves V, V₁ and V₂ will have closed their ports

only if pendulum 43 (Fig. 7) is in plumb with the trailer frame, out of plumb position of the pendulum will control the valves accordingly, raising or lowering individual rams R, R₁, R₂, and hold the position attained until the accumulator has exhausted itself through bleeder passage 38c (Fig. 14), enabling springs 105 to pull the pistons downwardly exhausting fluid through pipe 110 and applying cams 99 against shoes 98 locking all rams in this fixed position.

When operating member 42 is moved upwardly, pump P is switched on by switch S and operation is reversed since the return ports 50b, 51b and 52b are opened by the lowering of yoke arms 45. Fluid will again be pumped into cylinders 96 to release the brake, and into spaces 38 returning the rams to telescoped position. The fluid will thereafter also be exhausted as before from under pistons 97 allowing the cams 99 to clamp the rams in withdrawn position. Fluid in chambers 28 of cylinders 10 will be exhausted through outlets 70, 71, 72, passages 50a, 51a, 52a over the upper valves V, V₁, V₂ and into the tank.

While I have described and illustrated a preferred embodiment of my invention, it is to be understood that various modifications and rearrangements of parts may be made by those skilled in the art without departing from the scope of the invention as intended to be defined by the appended claims.

I claim:

1. A leveling device for structures including: a pendulum suspended from said structure and free to swing in any direction; a plurality of hydraulic rams mounted below said structure and adapted to be projected against a supporting surface; a pump; conduits connecting the output from said pump to said hydraulic rams; valves controlling said conduits; operative connections between said valves and said pendulum whereby movement of the pendulum operates the valves if the structure is not level, to supply liquid under pressure to particular rams to bring the structure into level position; means to operate said pump to supply fluid under pressure to said valves; locking means fitted to said rams; resilient means normally holding said locking means in position to prevent movement of said hydraulic rams, hydraulically operated means effective to release said locking means; conduits connecting said hydraulic means to the pump output so that the locking means are released when pressure fluid is supplied by the pump to the system; operative means for manually putting the pump into operation and for automatically putting it out of operation on a predetermined pressure of the hydraulic fluid being attained; spring loaded valve means effective to maintain the hydraulic pressure on the rams when the pump is put out of operation; and an escape conduit between the pump and said spring loaded valve connected to said hydraulically operated releasing means whereby hydraulic pressure is released from said means and the locking means are brought into action to hold the structure in level position.

2. A device as set forth in claim 1 and in which said source of fluid under pressure comprises a prime mover and pump driven thereby serving to supply fluid under pressure to said conduits, said means for setting the device into operation comprising a handle manually moved from neutral position to start said prime mover into operation and automatically returned to neutral position to stop said prime mover when the pressure

in all parts of the system has become stabilized.

3. A device as set forth in claim 1 and in which the hydraulic rams are double acting; movement of the operating means in the direction opposite to that putting the device into leveling operation acting to withdraw the hydraulic rams into telescoped position.

4. A device as set forth in claim 1 and in which said valves are positioned in a valve block; and a tank for hydraulic fluid secured to the structure in which said valve block and pendulum are arranged.

5. An automatic leveling system for structures including: a plurality of telescopic units applicable to and disposed at different points between the structure and a supporting surface therefor; a source of fluid under pressure, a freely swinging pendulum, and a valve block, both said pendulum and valve block being enclosed in a fluid containing housing; valve control means operated by said pendulum and also located in said housing; including inlet and outlet valves for each of the telescopic units; conduits connecting the fluid under pressure in said source with the telescopic members to both extend and retract them as determined by the operation of said valves; and means for setting the device into

operation, and to automatically cause termination of the operation of the device on the structure attaining a predetermined position, the operation of said latter means being independent of the level of the fluid in said housing.
